CLOCK

Andrew C. Klein, Jr., 425 Carsonia Ave.,
Pennside, Pa.

Filed May 23, 1966, Ser. No. 2,400

Term of patent 14 years

(Cl. D42—7)

FIGURE 1 is a front elevational view of a clock showing my new design.

FIGURE 2 is a reduced-scale side elevational view thereof, taken from the right side of FIGURE 1.

FIGURE 3 is a reduced-scale rear elevational view thereof.

The dominant features of my design reside in those portions shown in full lines.

The ornamentation at the corners extends over the entire face of the clock.

I claim:

The ornamental design for a clock as shown and described.
